TROLLEY WIRE HANGER

Samuel S. Matthes, Mansfield, Ohio, assignor to
The Ohio Brass Company, Mansfield, Ohio, a
corporation of New Jersey

Application October 19, 1945, Serial No. 623,216

5 Claims. (Cl. 287—14)

1

My invention relates to supports for trolley wires and has particular reference to those devices for supporting trolley wires forming a part of the overhead system for trolley bus operation.

In such systems the parallel trolley wires are placed some 18 to 24 inches apart and of opposite polarity. This requires sufficient and proper insulation between the wires which is one object of my invention.

Another object is to provide means for attaching supporting span wires to the device and which means is adjustable to compensate for the variable conditions met within overhead trolley constructions, thereby permitting proper positioning of the trolley wires.

Other objects and advantages will appear from the following description.

In the accompanying drawing illustrating my invention:

Fig. 1 is a side view in partial section of my invention arranged to support two trolley wires.

Fig. 2 is a view in partial section of the end cap I use before application to the connecting bar.

Fig. 3 is a side view showing a portion of the end cap in Fig. 2.

Fig. 4 is a side view of the adjustable arm I employ.

Fig. 5 is an edge view of Fig. 4.

Fig. 6 is a side view of a special bolt I use.

Fig. 7 is an end view of Fig. 6.

My improved hanger is so constructed that variation in the span wires used to support the trolley wires, may be easily adjusted such that the trolley wires may be installed and maintained in a horizontal plane at the hanger.

Sometimes the span wires to a hanger are of equal length and sometimes of greatly different lengths and often the far end of one span wire is attached to its support at a greater height than that of the other span wire. My invention will make it possible to compensate for such variations.

In the preferred embodiment of my invention I provide a connecting bar 1 of necessary length whereby the end members 2 may be held in spaced and insulated relation.

The member 1 may be of wood or of other approved construction or material. I prefer wood as it has been found dependable and economical.

The end members 2 are cup shaped as shown in Fig. 2 with projecting lugs 3 and 4 forming therebetween the space 5.

Both lugs 3 and 4 are provided with registering openings 6 and 7. The opening 7 is surrounded by a plurality of serrations 8.

2

The cup shaped member 2 has straight sides originally and the ends of the bar 1 have heads with tapered side walls and when the members 2 are positioned on the ends of the bar 1 and the side walls of the member 2 forced inwardly, a connection is secured which is equal or better than the minimum breaking strength of the bar.

The arms 9 are secured to the end members 2 in adjustable relation thereto and are so attached to the members 2 that they may be adjusted in a vertical plane to differ angular positions relative to the bar 1.

This adjustment is secured by the use of a bolt or pintle 10 having the under surface of its head 11 provided with serrations 12 to correspond to the serrations 8 on the end member 2.

The bolt 10 is further provided with an out-of-round shank 13, preferably square, and projecting from the shank 13 is a threaded portion 14 to take a nut 15.

Between the head 11 and shank 13 and between the shank 13 and threaded portion 14 are plain circular portions 16 which act as bearings in the openings 6 and 7.

The arm 9 has an opening 17 at one end which corresponds to the shape of the shank 13 and the other end has an eye 18 to receive a span wire.

To assemble the arms 9 in the slots 5 of the end members 2, the arms are first positioned in the slots 5 with the openings 6, 7 and 17 registering. The bolts 10 are then positioned in the openings with the serrations 12 on the bolt head cooperating with the serrations 8 on the lug 4.

This locks the arms 9 against pivotal movement about their pivotal centers which are the axes of the openings 6 and 7 because the shanks 13 are sufficiently long to enter well the openings 17 in the arms 9.

Since the opening 7 is round, the bolt 10 is free to rotate in the lugs 3 and 4 when the serrations are not interlocked.

When the arms 9 are properly positioned as to their angular relation to the axis of the bar 1, then nuts 15 are secured to the projecting ends of the threaded portions 14, employing a spring lock washer, if desired, to prevent its unscrewing.

If at any time it is found that the sag of the span wires supporting the device has changed so as to throw the trolley wires out of their proper horizontal relation, it is only necessary to loosen the nuts 15, push the bolts 10 back so as to break the cooperation of the serrations and move the arm about its pivotal point, then interlock the serrations and retighten the nuts 15.

As indicated by the dotted lines *a* at one end of Fig. 1, the arms may be adjusted to different positions and maintained in such adjusted positions.

The bar 1 is provided with means 20 to secure supports for the trolley wires to the device which comprise a pair of yoke members 21 and 22 held to the bar 1 by bolts 23, a pair to each support, which draw the yoke members in secure engagement with the bar 1. This permits the supports 20 to be adjusted along the bar.

Projecting from each support 20 in vertical alignment with the longitudinal axis of the bar 1 is a threaded stud 24 to which the trolley ear or clamp is secured.

Other equivalent means may be employed to adjust the arms but I have found the construction disclosed to be efficient, economical and permitting easy adjustment.

The supports 20 may be inverted if desired to support conductors above the bar 1.

The bar 1 may be of varying lengths depending upon the number of trolley wires to be supported, one or more.

While I have shown an adjustable arm at each end of the device, it is evident that the arm at one end may be omitted if found desirable and the span wire at that end secured in the slot 5 and held by the bolt 10. This would produce what is known generally as a single curve support.

The construction I have described brings the pull of the span wires or other supports upon the end members in line with the vertical plane of the bar 1, thus producing a balanced overhead construction.

My device is usable as shown as a straight line support or as a single or double curve support.

Having disclosed my invention, what I desire to secure by Letters Patent and claim is:

1. An article of manufacture comprising, a body member provided with means for attachment to another body member, the first said body member having fixed longitudinally projecting spaced lugs with substantially smooth inner faces, an arm having one end positioned in the space between the lugs, the lugs and the said one end of the arm having transversely disposed registering openings, a pintle extending through the openings by means of which the arm may be moved in a longitudinally disposed plane to change its angular relation with the longitudinal axis of the body member, the pintle provided with spaced bearing portions positioned in the lug openings whereby the pintle is rotatable relative to the lugs, means on the pintle intermediate the said spaced portions and means on the arm cooperating with the last said means whereby the arm is non-rotatable relative to the pintle but the pintle may be moved axially of the arm, means at one end of the pintle and other means on the other face of one lug to cooperate with the last means to prevent relative rotation of the pintle and lug and prevent the said angular movement of the arm relative to the said longitudinal axis and means on the other end of the pintle to engage the outer face of the other lug to prevent axial movement of the pintle and to maintain said cooperation of the said means on the pintle and on the lug.

2. An article of manufacture comprising a body member provided with means whereby it may be secured to another member and having fixed longitudinally projecting spaced lugs, an arm having one end positioned in the space between the lugs, the lugs and the said end of the

arm having registering openings the axis of which is transversely disposed to the longitudinal axis of the body and lugs, a pintle extending through the openings, means associated with the pintle and other means associated with the one lug and the said means cooperating to prevent relative rotation of the pintle and lugs, means on the arm and other means on the pintle cooperating with each other to prevent relative rotation of

10 the pintle and arm, and still other means on the pintle to cooperate with the other lug to prevent axial movement of the pintle transversely to the said longitudinal axis of the body and lugs, whereby the arm is held in angular adjusted relation to the said longitudinal axis.

3. An adjustable fitting comprising a cup-shaped body having an inwardly bendable wall and a pair of fixed and spaced lugs projecting longitudinally from the closed end of the body and each lug having a smooth inner face, the lugs provided with registering openings having smooth inner peripheral bearing surfaces and the bearing surface of one opening having a greater diameter than that of the other opening, a removable bolt member positioned in the openings, the bolt member having smooth spaced bearing portions corresponding in diameter to the bearing surfaces of the lugs and cooperating with the said bearing surfaces on the lugs and also having 20 an intermediate portion of irregular cross-section having a maximum diameter not greater than the diameter of the larger opening in the lugs, the bolt member having a projecting head portion at one end and a projecting threaded portion at the other end, an arm having one end provided with oppositely disposed smooth faces and positioned in the space formed between the lugs, the arm end being formed with an orifice of the shape of the intermediate portion of the bolt member and through which orifice the bolt member extends whereby the inadvertent displacement of the arm and rotation of the arm relative to the bolt member is prevented, locking means on the inner transverse face of the head portion of the bolt member and locking means on the outer transverse face of one of the lugs to cooperate with the locking means on the bolt member to prevent relative rotation of the bolt member and the cup-shaped body, and adjustable 30 means on the threaded portion of the bolt member to engage the other lug to maintain the cooperation of the said locking means after the parts have been adjusted.

4. An end fitting adapted for use on a trolley wire hanger comprising a cup-shaped body having an inwardly bendable wall, a pair of lugs in fixed and spaced relation projecting axially from the closed end of the cup-shaped body and each lug provided with an opening registering with the other opening, an arm having one end positioned in the space between the lugs and an opening through the said end of the arm, the arm movable in a plane coinciding with the longitudinal axis of the cup-shaped body to vary its angle with the longitudinal axis of the body, a bolt-like member extending transversely to the said axis and through the openings in the lugs and end of the arm and rotatable relative to the lugs, means on the bolt-like member and means on the arm to cooperate with the last said means to prevent rotation of the bolt-like member relative to the arm, means on the bolt-like member and other means on one lug to cooperate with the last said means to prevent rotation of the bolt-like member 50 when the angle of the arm has been adjusted rela-

tive to the longitudinal axis of the body, and means to maintain said cooperation between the said one lug and the bolt-like member.

5. An adjustable fitting comprising a metallic member provided with means to secure it to a body member and also having two projecting lugs in fixed spaced relation and having axially registering openings but one opening being larger than the other opening, an angularly adjustable arm having one end pivotally mounted in the space between the lugs, the arm having an opening through the said one end and registering with the other said openings, a pintle slidably positioned in the said openings and having spaced portions rotatable in the first said openings relative to the lugs, means on the pintle intermediate the spaced portions and other means on the arm arranged to cooperate with the said means on the pintle to prevent rotation of the pintle relative to the arm, means on the pintle and means on the outer face of one lug arranged to cooperate with the last said means on the pintle to prevent rotation of the arm and pintle relative to the lugs, and means on the pintle cooperating with the outer face of the other lug to prevent the pintle sliding and to maintain the cooperation of the said

means on the pintle and on the said one lug after the arm has been angularly adjusted relative to the lugs.
